[57] ABSTRACT

A slide fastener is provided with a reinforcing core or filler extending through a helical structure of a continuous row of fastener elements for stabilizing the position of the latter when sewn onto a carrier tape. The core or filler is a tubular structure designed to flexibly yield itself and fit snugly into the coil of each element.

FIG. 1

FIG. 2

SLIDE FASTENER HAVING A FILLING CORE**BACKGROUND OF THE INVENTION**

This invention relates to improvements in slide fasteners, more particularly to slide fasteners of the kind having rows of fastener elements made from a continuous filament or wire in the form of helical coils.

It has been the conventional practice to provide a reinforcing core or filler in the coiled element structure of fasteners of the kind described for increasing the positional stability of the rows of fastener elements relative to their respective carrier tapes and strengthening the coupling engagement of the fastener elements. Such core or filler is made usually of fibrous or plastic materials and has a solid cross section either circular or square.

Known slide fasteners employing such reinforcing cores have met with the difficulties that the core when sewn together with the fastener elements to the carrier tape fails to yield itself to the inner peripheral contour of the fastener elements having an oval or egg-shaped cross section, with the results that there are produced irregular gaps between the core and the leg portions and connecting portions of the coil elements. In other words, it has been difficult to hold the core in intimate contact uniformly with the inner periphery of each loop in a continuous coil fastener element row and in straight alignment with the longitudinal axis of the latter. Therefore, the conventional core, when sewn together with the row of fastener elements or otherwise subjected to pressure load, would serve adversely to cause objectionable deformation of the fastener elements and disturb the loop to loop spacing or pitch in the fastener element row. Sometimes, under the influence of external pressure the core makes a serpentine deflection such that the strength of coupling engagement between each loop of element differs throughout the length of the row of fastener elements and furthermore, the slider movement thereon is rendered extremely heavy at one place and conversely light at another.

SUMMARY OF THE INVENTION

Whereas, it is an object of the invention to provide improvements in slide fasteners of the type described whereby the aforesaid various difficulties of the conventional fasteners can be eliminated, such improvements being specifically directed to the physical structure of a reinforcing core to be employed for a helical coil type of fastener elements.

The above object together with other features of the invention will be apparent from the following description taken in conjunction with the accompanying drawings which illustrates by way of example a preferred embodiment of the invention.

BRIEF DESCRIPTION OF THE DRAWINGS

FIG. 1 is a plan view of a segment of a slide fastener according to the invention; and

FIG. 2 is a transverse cross-sectional view taken along the line II-II of FIG. 1.

DESCRIPTION OF THE PREFERRED EMBODIMENT

Referring to the drawings, there is shown a slide fastener 10 which comprises a pair of oppositely disposed

carrier tapes 11,12 each carrying along one longitudinal inner edge a row of continuous fastener elements E formed into a helical coil structure having successive loops E₁-E_n interengageable with those on the opposite tape. Each loop is cross-sectionally egg-shaped as seen in FIG. 2 and consists of a coupling head portion Ea, leg portions Eb and a connecting portion Ec as is usual with any known coil fastener element.

Extending longitudinally through the row of coil elements E is a reinforcing core 13 which in accordance with the invention has a tubular configuration with a hollow space 14 extending through its entire length. The reinforcing core 13 which constitutes an important feature of the invention may preferably be made of fibrous yarns knitted into a tubular form. Such knitted core may be further treated suitably with a synthetic resin. Alternatively, the core 13 may be formed by extrusion of a plastic material into a tubular structure. Any other alternatives may be considered provided that they are hollow and restorable in resiliency under conditions in which the fastener is used.

The advantage of the hollow core 13 according to the invention is that when inserted in the successive loops E₁-E_n and sewn together therewith to the respective carrier tape 11,(12) as by two-thread chain stitches S as shown, the core 13 can be brought into intimate contact with the internal peripheral surfaces of each loop including the leg portions Eb and connecting portions Ec but of course excluding the coupling head portion Ea lest the core 13 should interfere with the space in which adjacent loops engage with each other. The core 13 being hollow and hence resilient can readily yield itself at any given point in response to the sewing pressure or other external load and assumes a cross-sectional shape corresponding to the internal space of each loop defined by the leg portions Eb and connecting portions Ec. This takes place without imparting stresses to the fastener elements E which would otherwise result in deformed elements or disturbed element pitches.

The reinforcing core 13 according to the invention will thus serve its purpose of retaining the rows of fastener elements E stably in proper position on the carrier tapes 11,12, enhancing the strength of coupling engagement of the elements E uniformly throughout the length of the fastener, and further facilitating the smooth reciprocal movement of the slider along the rows of elements E.

What is claimed is:

1. A slide fastener comprising a pair of oppositely disposed carrier tapes, a row of fastener elements formed into a continuous helical coil structure and secured to each of said tapes, each element having a coupling head portion, leg portions and a connecting portion and a reinforcing core of a hollow tubular structure extending longitudinally through said row of elements in intimate contact with the internal peripheral surfaces of said leg portions and connecting portions of each element.

2. A slide fastener as defined in claim 1 wherein said core is made of fibrous yarns knitted into a tubular form.

3. A slide fastener as defined in claim 1 wherein said core is extruded of a plastic material into a tubular form.

4. A slide fastener as defined in claim 2 wherein said core is further treated with a synthetic resin.
